UNITED STATES PATENT OFFICE

WILLIAM H. RUSSELL, OF BALTIMORE, MARYLAND

BUTTER CUTTING MACHINE

Application filed February 1, 1928. Serial No. 251,125.

This invention relates to butter cutters, and particularly to that type of cutter in which the butter is expressed along a substantially horizontal plane, and is cut into individual portions by means of a transverse knife.

In large schools, hospitals, restaurants and the like, where it is necessary to serve a number of people at each meal, it is customary to purchase butter which is delivered in tubs. 10 It is the object of this invention to provide an improved device whereby such tub butter may be conveniently divided into small portions, although it is not intended, of course, that this device be considered applicable to 15 tube butter alone.

A feature of the invention is the provision of a novel butter chest having a cutting edge, whereby it may be inserted into a mass of butter and withdrawn in a loaded condition, 20 ready for subsequent operative attachment to the butter cutting machine proper.

Another feature lies in the construction of an adjustable handle for said butter chest, by means of which said chest may be handled 25 in either vertical or horizontal positions.

A further object is the provision of a butter cutting machine which may be conveniently and easily operated and motivated by a person seated therebefore, without the necessity of such person's manually touching the 30 butter at any time.

To this end the device is provided with a suitable actuating means, the nice adjustment of which is a further feature of the invention. 35

Yet another object is the provision of an improved automatic, adjustable, hinged receiving tray adapted to receive the butter after severance thereof into the aforesaid 40 small portions.

Another feature lies in an arrangement of parts whereby the expresser becomes automatically disengaged from the actuating mechanism upon reaching its prescribed limit 45 of travel, thus preventing damage to the machine through carelessness on the part of the operator.

Still another feature lies in so mounting the expresser that it may be readily adjusted to various angles with respect to a hori- 50

zontal plane, in order to facilitate the forward movement of the butter on the hinged tray of the device by means of gravity.

These, and such other objects as will be apparent upon perusal of the following detailed description, which is to be read in conjunction with the accompanying drawings, are contemplated in the present invention. It is to be understood that the device as hereinafter described is for the purpose of illustration only, and that such description is not to be construed as a limitation, since it is obvious that the invention may be variously embodied within the scope of the appended claims. 55

Referring to the drawings:

Fig. 1 is side elevation showing the device as a whole;

Fig. 2 is a fragmentary elevation of the expressing and cutting mechanism, being taken on the reverse side from that shown in Fig. 1, and showing the cross-cut knife in raised position; 70

Fig. 3 is a fragmentary plan view of the device as shown in Fig. 2, with the cross-cut knife in lowered position, and with the butter chest removed; 75

Fig. 4 is a sectional view taken substantially along line 4-4 of Fig. 3;

Fig. 5 is a fragmentary isometric view of the cutting plate and receiving tray; 80

Fig. 6 is a sectional view taken substantially along line 6-6 of Fig. 3, showing means for adjusting the receiving tray and cutting plate in parallel relation; 85

Fig. 7 is a fragmentary front elevation of the device as shown in Fig. 3, with the cross-cut knife in lowered position, and with the receiving tray in erect position;

Fig. 8 is a fragmentary isometric view of the adjustable handle on the butter chest; 90

Fig. 9 is a side view of the chest as shown in Fig. 8, showing the manner of inserting the same in a tub of butter; and

Fig. 10 is a top view of the chest as shown in Fig. 8. 95

The device is mounted on a suitable frame, which may consist of a number of legs 1, connected near the lower ends thereof by bracing members 2 and 3, and at their upper ends 100

by two longitudinally extending beams 4. A plank 5 is extended transversely across said beams at one end thereof, forming a table, said table being bounded on two sides by the ⁵ upstanding guards 6 and 7.

The brace 3 does not extend entirely lengthwise of the frame, but is discontinued between two adjacent legs whereby access may be had to the foot treadle 8.

16 Said treadle is pivotally mounted on the rear brace member 2, and is adapted to be oscillated in a vertical plane, between the parallel guide columns 9 and 10. The degree of oscillation of treadle 8 is limited by the stop members 11 and 12, one of said members being vertically adjustable. The adjustable stop member may consist of a pin adapted to be inserted through any two of the several registering openings 13, said pin being preferably surrounded with a rubber washer, as shown.

Pivottally attached to treadle 8 is the link 14, said link being rendered somewhat flexible by means of toggles 15. The upper end ¹⁴ of link 14 is pivotally and adjustably connected to lever 16, by means of a pin inserted through one of a series of openines as at 17. The lever 16 is keyed to a shaft 18 at the forward end thereof, and is adapted to rotate said shaft. At the far end of shaft 18 is keyed the lever 19, to the lower end of which is pivotally and adjustably connected the link 20, said link 20 being pivotally and adjustably connected to a crank 21. A counter-weight 22 is adjustably positioned on link 20, adjacent lever 19. This counter weight causes treadle 8 to automatically assume its uppermost position after each depression thereof, and at the same time brings crank 21 back to its initial starting position.

The various adjustments, as at 13 and 17, determine the degree of oscillation of crank 21, and hence determine the amount of forward displacement of the butter in the expresser, corresponding to each thrust on treadle 8, as will be hereinafter described.

A greater degree and nicety of adjustment has been found to be possible by means of the extra adjusting means provided in levers 16, 19 and 21, than would be practically expedient if the aforesaid degree of forward displacement of the butter were left to be determined by adjustment of the stop member 12 alone.

55 Crank 21 is rigidly connected between a pair of pawl-bearing disks 22 and 23, (Figs. 2 and 3) said disks being loosely rotatably mounted on shaft 24, and carrying on the outer faces thereof a pair of horizontally extending straps 25. Pivottally mounted between the forward extremities of straps 25 is an elongated pawl 26, said pawl being provided at the upper end thereof with a ⁶⁰ combined counter-weight and release-engag-

ing member 27. The pawl 26 is adapted to engage a ratchet 28, said ratchet being fixedly keyed to shaft 24.

Shaft 24 is journaled in bearings 29 and 30, said bearings being mounted on the vertically movable expresser frame 31. This frame consists of two parallel, longitudinally extending angle bars 31a and 31b, which are fixedly attached at their forward ends to the cutting plate 62, and which may be joined at the rear extremities thereof by any suitable transversely extending bracing member, such member being adapted to support a vertical column 40, for the purpose hereinafter described. Extending parallel with and positioned above members 31a and 31b, are two guiding members 32a and 32b, which may also be formed of angle iron. These guide members are fixedly attached to cutting plate 62 at their forward ends, and are at their rear ends curved down into engagement with bars 31a and 31b, and respectively attached thereto. The members 31 and 32 form a guideway and support into which a butter chest 103 may be inserted.

90 Centrally positioned on shaft 24 is a pinion 34 (Fig. 4), adapted to mesh with a longitudinally extending rack 39, said rack having on its forward end a butter displacing piston 45. Pinion 34 is mounted within a gear housing 35, which housing consists of a pair of erect enclosing plates seated on an upper saddle plate 36, said saddle plate extending transversely between members 31a and 31b. Spaced from and positioned below plate 36 is a lower saddle plate 37, said lower plate extending rearwardly somewhat beyond upper plate 36.

95 Rigidly fastened to the upper portion of gear housing 35 is the guide rod 38, said rod terminating forwardly at the forward edge of housing 35 and extending rearwardly to the end of the expresser frame, where it is fastened to and supported by column 40.

100 Slidably suspended from guide rod 38, and fixedly carried by rack 39 is an impact member 41, this member consisting of two side plates depending from either side of and surrounding rods 38 and 39, said plates being joined at their upper and lower ends by transverse webs, said upper web being provided with a tightening screw 42, the purpose of which is to prevent play between rods 38 and 39, and said lower web being adapted to support a hammer 43 which may be adjustably positioned thereon by means of a screw 44.

105 This hammer is adapted to actuate an automatic release mechanism whereby the forward motion of piston 45 may be discontinued when said piston reaches a predetermined limit of travel.

110 This release mechanism is most clearly shown in Fig. 4 and Fig. 2, and consists of a

trigger 46, which is shaped so as to slide between saddle plates 36 and 37, and be guided between the walls of housing 35. The upper side of trigger 46 is provided with an upstanding shoulder 47, which is adapted to be impinged by hammer 43. A rack 48 is formed integrally with the lower side of trigger 46; this rack meshes with a pinion 49 which is keyed to a shaft 50. Shaft 50 is provided at one end with a rearwardly depending, fixedly attached crank 51, having near one end a pin 52 which is slidably inserted in a slot 53a within a downwardly depending arm 53. Said arm 53 is formed integrally with a carriage 54, which carriage is adapted to slide within the slotted bearings 55 and 56, these being mounted on the bar 31a. Carriage 54 is provided at the forward end with an upstanding lug 57, which is adapted to engage pawl 26. A second lug 58 is positioned on carriage 54 adjacent the rearward end thereof. This second lug is adapted to engage a pawl 59, which is pivotally mounted on bearing 56, said pawl 59 being provided to prevent the backward coasting of ratchet 28.

It will be seen that as piston 45 approaches cutting plate 62, hammer 43 will approach shoulder 47, finally contacting with the same. This point of contact may be finely adjusted by means of screw 44, thus leaving a minimum residue of uncut butter between piston 45 and cutting plate 62 after each operation of the machine. As trigger 46 is pushed forward by hammer 43, rack 48 rotates shaft 50 thru pinion 49, thus swinging crank 51, causing pin 52 to push arm 53 and carriage 54 in a rearward direction. This causes lugs 57 and 58 to engage pawls 26 and 59, respectively, and throw the same out of engagement with ratchet 28, thus preventing the further rotation of shaft 24, despite any inadvertently continued oscillation of the crank 21.

The shaft 50 is further provided at one end thereof with a handle 60, whereby the pawls 26 and 58 may at any time be released from driving and restraining engagement with ratchet 28, thus making it possible to retract piston 45 by means of a hand-wheel 61 which is keyed to one end of shaft 24, as may be clearly seen in Fig. 3.

Piston 45 is adapted to slide within a detachable butter chest 103, the novel construction of which will be further described, thus forcing the butter therein contained through an erect cutting plate 62.

The cutting plate 62 (Fig. 5) is provided with a substantially centrally positioned rectilinear opening 63, which opening is reticulated by the cross threaded cutting wires 64, the ends of said wires being attached to adjustable tensioners 65. These wire tensioners 65 are formed of a strip of metal bent upwardly at the ends thereof, thus forming a U-shaped slider, which slider is mounted in

a suitably grooved member 66, said member 66 being fastened to plate 62 at the edge thereof, as can be readily seen by reference to Figs. 2 and 5. A thumbscrew is inserted thru the outer bifurcation of U-shaped member 65 and is made to bear on fixed member 66. An end of one of the wires 64 is fastened to the remaining bifurcation of member 65. It will be readily seen that as the slider is forced outwardly by the thumbscrew, the wire will be tightened in the desired manner. The tensioners on the top and sides of cutting plate 62, and on a cross-cut knife 98 are of similar construction.

The cutting plate 62 has rigidly fastened at the lower outer corners thereof bearings 67 (Figs. 5, 6, 7) which bearings are rotatably mounted on a shaft 68 journalled in a pair of bearings 69 which are fastened to beams 4. Thus it will be seen that the expresser frame bars 31a and 31b, which have been described as being rigidly attached in any suitable manner to the rearward side of plate 62, and all the parts appurtenant thereto, are rotatable in a vertical plane about the shaft 68 as an axis. That is to say, the expresser frame and butter chest are adapted to assume various convenient angles with respect to a horizontal plane. Said expresser frame is rearwardly supported on the moving struts 70 and 71, by means of a rod 72 insertable thru any two of a series of registering openings in said struts.

The struts 70 and 71 are longitudinally slideable along beams 4, to a sufficient extent to allow for the fitting of rod 72 therein, corresponding to the different angles of the expresser frame 31. It will be understood that since the remaining working parts of the device are pivotally jointed throughout, the above adjustment can be readily made.

A hinged receiving tray 80 is provided, this tray being adapted to be held in an erect position by a counter weight and to be lowered at will by means of a knee lever. To effect this, a pair of bearings 73 and 74 are pivotally mounted on shaft 68, and are joined at the upper ends thereof by a bridge 75. The bearings 73 and 74 and bridge 75 are free to move with respect to bearings 67 and cutting plate 62. Centrally of bridge 75 and beneath opening 63, are mounted a pair of bearings 76 and 77, having flat buffing faces 78 on the forward edges thereof. These bearings 76 and 77 carry a rod 79, on which is hinged the receiving tray 80. This tray is formed with an inner portion 81 which forms a slot on the inner side of the tray which is adapted to support a sheet of waxed paper to which the severed portions of butter will adhere.

The upper surface of this portion 81 provides a ledge for supporting the butter just after it is severed from the main mass left in the chest. The sheet of waxed paper is of

a size greater than the size of opening 63 in the cutting plate, whereby a free margin is left on the paper for gripping the same for removal from tray. In this way, it is not necessary to touch the butter itself at any time.

5 The portion 81 rests against the buffer faces 78 when tray 80 is in erect position, sufficient space being left between the plate 62 and tray 80 to accommodate the maximum thickness of butter desired to be cut. It follows that 10 the angular relation between the plane of tray 80 in its upright position, and that of cutting plate 62 will be dependent on the angular relation between the buffer faces 78 and said plate 62. In order to make adjustments 15 regarding this latter relationship, and thus keep tray 80 and plate 62 in parallel alignment, the bridge 75 is provided near each end with an upstanding projection 82, 20 adapted to receive a threaded bolt 83. This bolt is passed through a slightly elongated opening in cutting plate 62, and adjustably anchored on either side thereof by means of locknuts 84 and 85. As can be readily seen 25 by reference to Fig. 6, rotation of the bolt 83 will cause the bridge 75 and bearings 76 and 77 to rotate about 68 as an axis, and will thus cause buffer faces 78 to assume a new angle with respect to cutter plate 62.

30 It will be appreciated from the above description that I have provided means whereby the receiving tray and cutting plate may be easily kept in true parallel alignment, even after continued use of the device.

35 Pivotedly attached to the outer side of tray 80 is a link 86, which is pivotally attached to a lever 87. This lever is fixedly attached to a rod 90, said rod being fixedly inserted in the bearings 91 and 92 which are rotatably 40 suspended from rod 68. The lever 87 has a portion 88, which extends downwardly and rearwardly beyond rod 90, and to which is fastened a counter-weight 89. This counter-weight is adapted to force tray 80 into an 45 upright position after each depression thereof by the means about to be described.

50 Fixedly attached to rod 90 is a forwardly extending lever 93, and depending therefrom is a rod 94, said rod being adapted to contact 55 with a knee lever 95, which is pivotally mounted at one end to a beam 4, and slidably supported adjacent the other end by means of a suspension bracket 96. As the knee lever 95 is pushed into engagement with rod 94, lever 93 is depressed, carrying rearwardly and downwardly with it the rod 90, which 60 depresses lever 87 and so lowers tray 80. By means of the disclosed arrangement of parts, a very slight angular displacement of knee lever 95 will cause tray 80 to descend through an angle of approximately 90 degrees.

65 Since the expresser frame 31 is placed in a tilted position, as described above, the vertical line through the center of gravity of the tray 80 will descend forwardly beyond the axis 79 of said tray. Because of this arrangement, the weight of the tray constantly urges its descent forwardly and outwardly about its axis 79. This tendency to descend is overcome by the counterweight 89. Only 70 a slight impulse need be given to knee lever 95 to effect a prompt responsive dropping of the tray 80. A comparatively greater impulse would be needed to overcome the inertia of this tray if the latter were normally maintained in a vertical plane. Also, a more important result of the tilting of the cutting frame lies in the fact that such tilting acts to overcome the tendency of the butter that has been severed by the cross-cut knife 99 75 to adhere to the main mass of butter in the chest. The forward tilting of the cutting frame permits the severed butter to drop away from the remaining butter in the chest at the cutting frame 62, thus enabling such butter to follow, or drop with the tray 80 80 in its forward and outward path.

Pivoted tensionally, by any suitable means, near one edge of cutting plate 62 is a cross-cut knife, which consists of a U-shaped frame 97, carrying a handle 98. A cutting wire 99 is tensionally strung between the arms of frame 97, and a catch 100 is provided to halt the downward swing of handle 98. A counter-weight 101 is attached to the knife to 95 effect the automatic return thereof to an upright position, upon release of handle 98, and a rubber bumper 102 is fastened to frame 4 at the point of impact of said weight.

The butter chest 103 (Sheet 4) is formed 100 of relatively thin sheet metal, and is of a rectangular section exactly corresponding to opening 63 in the cutter plate. This chest is designed to be removed bodily from between guides 32a and 32b, and to be inserted in a 105 tub, or other container of butter. The forward edge 104 is of thin sheet metal sufficiently sharpened to be readily inserted as described. To facilitate the vertical insertion of chest 103 into a mass of butter, and to allow the said chest to be carried horizontally 110 during the subsequent portage between butter tub and machine, a novel handle is attached to the chest at the end remote from cutting edge 104. This handle is mounted on a thickened reinforcing binding 105, and consists, in part, of a pair of projecting L-shaped supports 106 and 107, between the forward 115 extremities of which is attached the cylindrical handle 108. Rotatably mounted on handle 108 are two side straps 109 and 110, which have extending between the lower ends thereof a handle 111. Said handle 111 is adapted to be grasped by one hand in conjunction with a handle 112 which is fixedly mounted on the binding 105, while handle 108 is 120 grasped by the other hand. The chest is then ready to be vertically inserted in a mass of butter, sufficient pressure being applied thereon thru the described handles. Obviously it 125

130

is desirable to carry the chest, so loaded, in a horizontal position, and to this end straps 109 and 110 may be rotated about handle 108 thru an angle of 270 degrees, until they 5 assume the position shown in Figs. 1 and 2, where they will be locked. This locking means consists of a pair of tumblers 113 and 114 projecting perpendicularly from straps 109 and 110 respectively, and having the outer 10 ends thereof curved as shown at 114a. These tumblers are designed to engage a retractile spring latch 115, said latch having curved engaging faces at 116 and 117. Latch 115 is 15 slidably mounted in two slots in members 106 and 107, and upon contact of tumblers 113 and 114 with faces 116 and 117, will be forced to recede until said tumblers are completely beyond shoulders 118 and 119, at which time a compression spring 120 will cause latch 20 115 to resume its former position and lock the tumblers in their newly assumed position, thus holding straps 109 and 110 in the 25 positions shown in Figs. 1 and 2. A knob 121 is provided whereby latch 115 may be moved over to release tumblers 113 and 114 and allow straps 109 and 110 to be swung back to the position shown in Fig. 8.

In operation of the machine the handles on chest 103 are first placed in the position 30 shown in Fig. 8, and the chest is inserted in a mass of butter in the above described manner. The chest is then withdrawn and held by means of handle 112, until straps 109 and 110 are swung around and locked in the position 35 shown in Fig. 1. The chest may then be carried in a horizontal position by means of handle 111, the parts being so proportioned that the center of gravity of the loaded chest will lie approximately vertically below 40 said handle. With handle 111 in the position shown in Fig. 1, the chest is positioned between guides 32a and 32b and is slid forward until edge 104 contacts with cutting plates 62 adjacent the edges of opening 63. In order 45 to effect this positioning of the chest 104, it is first necessary to turn back piston 45 to its extreme rearward limit of travel, by means of hand wheel 61, ratchet 59 being free. After the butter chest is in place, piston 45 50 is moved forward into proximity with the butter therein contained, by means of hand wheel 61. The handle 60 is then thrown over, which moves carriage 54 forwardly and allows pawls 26 and 59 to engage ratchet 28, 55 ready for operation.

The operator is then seated before the device adjacent the treadle 8. A sheet of waxed paper is inserted in the pocket of tray 80, a suitable supply of the former being kept 60 in a convenient container 113. The treadle 8 is then depressed, causing crank 21 to be oscillated rearwardly by means of the bell crank arrangement at 16 and 19, and the links 14 and 20. As the crank 21 is so oscillated, the pawl bearing plates 22 and 23

rotate about 24, causing pawl 26 to bite and rotate ratchet 28, thus partially rotating shaft 24. As shaft 24 is rotated, rack 39 is urged forward thru means of pinion 34, the amount of such forward movement being determined by the degree of oscillation of crank 21, which may be varied as hereinbefore described. Piston 45 thus forces a certain predetermined amount of butter thru cutting frame 62 with each depression of treadle 8. 70 This butter is cross-cut by means of knife 97, after which tray 80 is depressed by means of lever 95, a suitable root rest 114 being provided to aid the latter action. The severed portions of butter will adhere to the 75 waxed paper, and may be removed thereon, thus obviating the necessity of handling the butter, and a fresh sheet of paper may then be inserted in the tray pocket. The tray 80 will automatically rise upon release of lever 80 95, because of weight 89, and crank 21 will assume its initial position upon release of treadle 8, because of weight 22. The operation is so continued until hammer 43 automatically disengages the actuating mechanism, whereupon piston 45 is retracted by 90 means of hand wheel 61, the chest removed and filled again, the process so continuing until the desired number of portions have 95 been cut.

It has been found that the use of counterweights, rather than springs, effects a desirable smoothness of operation, and that columns 9 and 10 transmit any shock caused by reciprocating parts directly to the floor. 100

Having described my invention, what I claim as new, and desire to secure by Letters Patent is:

1. In a butter cutting machine, a butter holding chest having a stationary handle and a pivoted handle adapted to hold said chest in vertical or horizontal positions, said pivoted handle being cooperable with said stationary handle in one of said positions. 105

2. A butter holding chest having a pivoted handle adapted to hold said chest in vertical or horizontal positions, said handle comprising a fixed grip, a movable grip spaced from said fixed grip, means for rotating said movable grip about said fixed grip as an axis 110 whereby said movable grip can be halted in a plurality of supporting positions, and means for locking said movable grip in one of said supporting positions. 115

3. In a butter cutting machine, a cutting plate, means for expressing a mass of butter through said cutting plate, means for severing portions of said butter from the mass, a tiltable tray for receiving said butter after severance thereof, said tray being pivotally mounted adjacent one edge of said cutting plate, members having buffer faces engaging said tray when the same is in normal position, said faces being in a plane substantially parallel to the plane of said cutting plate, 120 125 130

and means for adjusting the plane of said buffer faces with respect to the plane of said cutting plate.

4. In a butter cutting machine, a butter holding chest, having a cutting edge thereon for filling the same, and a pivoted handle on said chest adapted to assume a plurality of positions with respect to said chest, said handle being spaced from the butter engaging portions of said chest in any of said positions.

5. In a butter cutting machine, a cutting plate, a receiving tray hinged upon an axis adjacent one edge of said cutting plate, a rocker having one end thereof flexibly connected with said tray, and having the other end thereof mounted pivotally upon the butter cutting machine, and force applying means for moving said rocker to depress said tray, said force applying means engaging and acting upon said rocker at a point between said pivotally mounted and flexibly connected ends.

6. In a butter cutting machine, a cutting plate, a receiving tray hinged upon an axis adjacent one edge of said cutting plate, an oscillatable U-shaped element mounted on the butter cutting machine, a member fixed to said U-shaped element, a link flexibly connecting said member and said tray, and an oscillatable lever adapted to swing said U-shaped element whereby said tray is oscillated.

7. In a butter cutting machine, a rack having a butter displacing plunger fixedly attached thereto, an oscillatable lever for actuating said plunger, clutch means including a pawl on said lever operatively connecting said plunger and said oscillatable lever whereby continued oscillation of the latter causes intermittent and progressive movement of the rack and plunger and means for limiting the movement of said rack and plunger, such limiting means including a rigid member adapted to engage said pawl and push the same to inoperative position, and also including a member on said rack for actuating said pawl engaging member.

8. In a butter cutting machine, a rack having a butter displacing plunger fixedly attached thereto, an oscillatable lever for actuating said plunger, clutch means including a pawl on said lever operatively connecting said plunger and said oscillatable lever whereby continued oscillation of said lever causes intermittent and progressive movement of said rack and plunger, actuating means for moving said oscillatable lever in one direction, and means automatically moving said lever in the other direction and means for limiting the movement of said rack and plunger, such limiting means including a rigid member adapted to engage said pawl and push the same to inoperative position,

and also including a member on said rack for actuating said pawl engaging member.

9. In a butter cutting machine, a butter displacing plunger, actuating means for propelling said plunger, including a pawl and a ratch, release means including a slidable rack, a pinion meshed with said rack, and a member actuated by said pinion for disengaging said pawl from said ratch, and means carried with said plunger for operating said slidable rack.

10. In a butter cutting machine, a butter displacing plunger, actuating means for propelling said plunger, including a pawl and a ratch, release means including a slid- 80 able rack, a pinion meshed with said rack, and a member actuated by said pinion for disengaging said pawl from said ratch, means carried with said plunger for operating said slidable rack, and supplemental 85 manual means for operating said member.

11. In a butter cutting machine, a butter holding chest, a cutting frame at one end of said chest, a plunger insertable in the other end of said chest, a rack on said plunger for propelling the same, means for propelling said rack, said means including a pawl and ratch, a sliding carriage having a rigid portion thereof adapted to engage said pawl and trip the same out of engagement with 95 said ratch, an impact member positioned on said rack, said impact member being adapted to move said sliding carriage after a pre-determined movement of the rack toward the cutting plate for tripping said pawl. 100

12. In a butter cutting machine, a cutting means, and a butter receiving tray tiltably mounted in position to receive the butter cut by said cutting means, said tray having a slot extending across the lower part thereof, 105 said slot being adapted to receive a butter receiving member.

13. In a butter cutting machine, a cutting plate, an opening substantially centrally disposed in said plate, a butter receiving tray 110 tiltably mounted adjacent one edge of said cutting plate, a supporting ledge extending across the lower edge of said tray, said ledge being even with and adjacent one edge of the opening in said cutting plate when said tray is in normal position, said tray being slotted between said ledge and the body of said tray.

14. In a butter cutting machine, a cutting plate, a butter-receiving tray mounted 115 for swinging movement with respect to the plate and having a normal position substantially parallel with the plate, and means connected to and adjustable with respect to the plate for predetermining the normal position of the tray relative to the plate.

15. In a butter cutting machine, a cutting plate, a rod supported thereby, a bridge mounted for swinging movement on said rod, 120 a tray mounted for swinging movement on 125

the bridge, and means for adjusting the bridge with respect to the cutting plate.

16. A butter cutting machine including a frame, a cutting plate mounted for swinging movement with respect thereto, a bridge mounted for swinging movement with respect to the cutting plate, means for adjusting the bridge with respect to the cutting plate, a tray mounted for swinging movement with respect to the bridge to permit the tray to move toward and from the cutting plate, and means carried by the bridge and movable in the adjustment thereof to selectively control the relation of the cutting plate and tray in one limit position of the latter.

17. In a butter cutting machine, a frame, a rod extending transversely of the frame, a cutting plate mounted for swinging movement on said rod, a bridge mounted on said rod for swinging movement independently of the plate, a rod carried by the bridge, a tray pivotally supported on the bridge-carried rod, stops carried by the bridge to limit the movement of the tray toward the cutting plate, and means for adjusting the bridge and thereby the stops to predetermine the relation of the tray and cutting plate in one limit position of the tray.

18. In a butter cutting machine, a frame, a cutting plate mounted for swinging movement with respect to the frame, a tray movable from a receiving position adjacent the plate to a discharge position at an angle to the plate, a tray mounting on which the tray is swingingly supported, said mounting being movable about the center on which the plate is movable, means for adjusting the mounting with respect to the plate, and tray-limiting stops carried by and movable with the mounting for determining the receiving position of the tray.

19. In a butter cutting machine, a frame, a cutting plate mounted for swinging movement with respect to the frame, a tray movable from a receiving position adjacent the plate to a discharge position at an angle to the plate, a tray mounting on which the tray is swingingly supported, said mounting being movable about the center on which the plate is movable, means for adjusting the mounting with respect to the plate, tray-limiting stops carried by and movable with the mounting for determining the receiving position of the tray, means for normally holding the tray in receiving position, and manually operable means for moving the tray to a discharge position.

20. In a butter cutting machine, a frame, a cutting plate, a tray mounting, means carried by the frame providing a common center for the plate and tray mounting, means for adjusting the tray mounting with respect to the plate, and a tray pivotally supported on the mounting and movable from a receiv-

ing position adjacent the plate to a discharge position at an angle to the plate.

21. In a butter cutting machine, a frame, a cutting plate, a tray mounting, means carried by the frame providing a common center for the plate and tray mounting, means for adjusting the tray mounting with respect to the plate, and a tray pivotally supported on the mounting and movable from a receiving position adjacent the plate to a discharge position at an angle to the plate, said tray being formed to removably receive and support a section of material on which the butter may be delivered.

22. In a butter cutting machine, a frame, a butter cutting plate, a tray mounting, a rod mounted on the frame forming a common center for the plate and tray mounting, means for adjusting the tray mounting with respect to the plate, a tray swingingly supported on the mounting, means supported by the rod for normally influencing the tray to a receiving position adjacent the plate, and manually operable means supported by the frame for compelling a movement of the tray away from the plate for discharge purposes.

23. In a butter cutting machine, a frame, a cutting plate, a tray mounting, a rod mounted on the frame and forming the common center for the tray mounting and plate, means for adjusting the position of the tray mounting with respect to the plate, a second rod carried by the tray mounting, a tray swingingly supported on said second rod, hangers depending from the first mentioned rod, means carried by the hangers and connected with the tray for normally holding the tray in receiving relation to the plate, and manually operable means for moving the tray away from the plate to a discharge position.

24. A butter holding chest for butter cutting machines including a hollow body open at the ends and otherwise closed, a fixed handle carried by the body, and a movable handle carried by the body, said movable handle in one position cooperating with the fixed handle for manipulating the chest in loading and in another position overlying the chest substantially intermediate the open ends thereof.

25. A butter chest for butter cutting machines including a hollow body open at the ends and otherwise closed, a handle movably mounted on the body adjacent one end thereof whereby the handle may be swung across one open end of the body or to a position overlying one closed side of the body, means for securing the handle in the latter position, the handle when in a position across the end of the body serving to permit endwise manipulation of the body for loading the chest, said handle when in a position overlying one closed side of the body serving as a means for carrying the loaded chest.

26. In a butter cutting machine, a material

receiving chest, a cutter plate arranged at one end thereof, a plunger movable in the chest to force material to and through the cutter plate, feeding mechanism for the plunger including a pawl and ratchet, manually operable means for actuating the feeding mechanism through the pawl and ratchet, a member cooperating with the pawl to interrupt the manual control of the feeding means, and means carried by the plunger to operate said member at a predetermined point in the travel of the plunger, said member moving in a direction opposite to that of the plunger in its pawl control movement.

27. In a butter cutting machine, a material receiving chest, a cutting plate arranged at one end thereof, a plunger operative in the chest for forcing material to and through the cutter plate, means for imparting a step by step movement to the plunger, said means including a pawl and ratchet mechanism, a member slideable in a direction opposite to the movement of the plunger for cooperation with the pawl to move the pawl out of cooperative relation with the ratchet, an impact element carried by the plunger to operate said member following a predetermined movement of the plunger, and means carried by the impact element to adjustably vary its control of the member to insure exact predetermined limits to the plunger movement.

28. In a butter cutting machine, a material receiving chest, a cutter plate arranged at one end thereof, a plunger movable in the chest to force material to and through the cutter plate, feeding mechanism for the plunger including a pawl and ratchet, manually operable means for actuating the feeding mechanism through the pawl and ratchet, a member cooperating with the pawl to interrupt the manual control of the feeding means, means carried by the plunger to operate said member at a predetermined point in the travel of the plunger, said member moving in a direction opposite to that of the plunger in its pawl control movement, and means whereby the member may be manually operated at will.

29. In a butter cutting machine, a cutting plate, a receiving tray hinged upon an axis adjacent one edge of said cutting plate, an oscillating U-shaped element comprising upstanding arms and a cross piece, said U-shaped element being pivotally mounted on the butter cutting machine at the ends of the arms thereof, a member fixedly attached to said cross piece, a link flexibly connecting said member and the tray, and means for moving said U-shaped element, said means applying force to said U-shaped element at a point between the ends of one arm and the point of attachment of said member.

In testimony whereof I affix my signature.
WILLIAM H. RUSSELL.
